ERNST SANDIG, OF BERLIN, GERMANY, ASSIGNOR TO THE FIRM JULIUS FRIED-LAENDER, GUMMIWAREN-FABRIK, G. M. B. H., OF BERLIN, GERMANY

MEDICAL SYRINGE

Application filed August 21, 1928, Serial No. 301,118, and in Germany September 12, 1927.

The invention relates to enemas and like medical syringes, intended more particularly for use when travelling.

According to the invention a wrapper or cover, which may be of rubber or other foldable, waterproof material, has on its inside a foldable container for the liquid, to which the syringe tube is connected, so that when the appliance is not in use the container and the tube may be wrapped up in the cover. The container may be held in a sheath on the inside of the cover, or may be integral with the cover.

Two embodiments of the invention are shown in the accompanying drawing, in Figs. 1 and 2 and in Fig. 3 respectively.

Fig. 1 shows the appliance unfolded, with the tube in the pocket.

Fig. 2 shows it folded.

Fig. 3 shows the appliance unfolded, with the tube (partly broken away) outside the pocket.

Referring first to Figs. 1 and 2, *a* is the cover sheet and *b* is a smaller sheet attached thereto to form a sheath on the inside of the cover, *c* being a pocket, also on the inside. The foldable liquid container *d* is inserted into the sheath formed by the sheets *a* and *b*, and the syringe tube *f*, when not in use, is placed in the pocket *c*. There is an eye *e* in the cover, for hanging it up while in use. The cover has spring buttons and sockets *g*, for fastening it when folded.

In the modification shown in Fig. 3 there are a cover sheet *a*¹ and pocket *c*¹, similar to the cover and pocket described with reference to Figs. 1 and 2, the cover having an eye *e*¹ and buttons and studs *g*¹, but the liquid container is formed in part by the cover itself and in part by a sheet *b*¹ having its sides and bottom edges attached to the cover, an outlet *d*¹ being provided at the bottom, to which the syringe tube *f*¹ is connected. In this case also the tube is placed in the pocket, when not in use.

What I claim as my invention and desire to secure by Letters Patent of the United States is:—

1. A medical syringe, comprising a foldable cover sheet, a foldable liquid containing

pouch arranged on one side of said cover sheet intermediate the ends thereof, a syringe tube connected to said pouch, and a pocket on the same side of said cover sheet for said tube, said cover sheet being adapted to be folded around said pouch and said tube. 55

2. A medical syringe, comprising a foldable cover sheet, a foldable liquid containing pouch integral with said cover sheet and arranged on one side thereof, and a syringe tube 60 connected to said pouch, said cover sheet being adapted to be folded around said pouch and said tube.

3. As a new article of manufacture, a medical syringe comprising a foldable cover sheet 65 and a foldable liquid containing pouch arranged on one side of said cover sheet intermediate the ends thereof, said cover sheet being adapted to be folded up flat with said pouch on the inside thereof. 70
